(57) **CLAIM**

The ornamental design for jewelry, as shown.

DESCRIPTION

FIG. 1 is a perspective view of jewelry showing my new design; and,

FIG. 2 is a front elevation view thereof.

The broken lines depicting portions of the jewelry form no part of the claimed design. The rear of the jewelry is unornamented and also forms no part of the claimed design.

1 Claim, 2 Drawing Sheets

FIG. 1

FIG. 2
